BY Fetherstonhaugh & Co

ATTYS.

UNITED STATES PATENT OFFICE.

FREDERICK STANLEY LONG, OF WINNIPEG, MANITOBA, CANADA.

CARD-INDEX HOLDER.

1,360,548.

Specification of Letters Patent. Patented Nov. 30, 1920.

Application filed July 1, 1919. Serial No. 307,922.

To all whom it may concern:

Be it known that I, FREDERICK STANLEY LONG, a subject of the King of Great Britain, and resident of the city of Winnipeg, 5 in the Province of Manitoba, Dominion of Canada, have invented certain new and useful Improvements in Card-Index Holders, of which the following is a specification.

This invention relates to improvements 10 in index card holders of the type designed to maintain a plurality of cards in stepped relation, whether in a cabinet or not, and the objects of the invention are to provide simple means for holding the cards in position 15 in such a way that they may be more readily visible, and better adapted for sorting and like purposes, and it consists essentially of the card holder having a plurality of inclined slots of varying length adapted 20 to support the cards in inclined and stepped relation, all as hereinafter set forth and described in the accompanying specification and drawings.

In the drawings:—

25 Figure 1 is a cross sectional view through an embodiment of the invention.

Fig. 2 is a perspective view of the card holder.

30 In the drawings, like characters of reference indicate corresponding parts in all the figures.

Referring to the drawings, A indicates a cabinet divided into two compartments 10 and 11 by a partition 12. The compartment 35 10 is designed to contain any convenient card index arranged with suitable dividing cards. The compartment 11 contains a card supporting element B which may be used separately from the cabinet as a card holder 40 indicated in Fig. 2.

The card supporting element or rack B is of inverted U-shape, and may conveniently be formed of sheet metal formed on the top with a plurality of parallel slots 13 45 which meet inclined parallel slots 14 in the sides, the slots 14 being gradually increased in depth from one side to the other of the rack, whereby when the cards are placed in the slots they will be held in inclined 50 stepped relation.

It will be observed that the slots 14 being inclined in normal position will hold the

cards in such a position that they are readily visible and will have their edges presented in a more convenient position for 55 sorting.

D represents the forward cover hinged to the side 15 and designed to swing downwardly to form a tray which may contain a scratch pad or the like indicated in dotted 60 lines in Fig. 1.

When closed this portion of the cover will cover the compartment 10, while the compartment 11 will be covered by a cover E hinged to the rear part of the cabinet. 65

The dimensions of the supporting member B are such that it will fit conveniently into the compartment 11 as shown. The cards are only designed to be held in the rack temporarily, but it will be seen that by reason of their stepped and inclined relation the outer portion of each card will be in view, and the various appointments, etc., will be quickly observed. 70

It will be observed that the slots 14 and 75 13 cause the outer part of the member B to be divided into a plurality of spaced fingers 16 which support the cards between them in spaced, stepped and inclined relation. 80

As many changes could be made in the above construction, and many apparently widely different embodiments of my invention, within the scope of the claim, constructed without departing from the spirit 85 or scope thereof, it is intended that all matter contained in the accompanying specification and drawings, shall be interpreted as illustrative and not in a limiting sense. 90

What I claim as my invention is:— 90
A card index cabinet formed with a front and rear compartment, a card supporting element or rack of inverted U-shape in the rear compartment, the rack having inclined slots forming spaced fingers between which 95 the cards are adapted to lie in stepped, spaced and inclined relation.

In witness whereof I have hereunto set my hand in the presence of two witnesses.

FREDERICK STANLEY LONG.
